GAS BURNER

Application filed April 5, 1928. Serial No. 267,559.

My invention relates to gas burners and has to do particularly with burner structure of a character well adapted for use with gas-heated water heaters, furnaces and boilers for heating systems, stoves, gas refrigerators, vats, and the like, and wherein the gas flow to the burner may be controlled over a wide pressure range by thermostatic (or other automatic) or hand-controlled means. One of the main objects of my invention is to provide a universal burner structure which is capable of maximum efficiency in operation over a wide range of gas pressures from a minimum low pressure (slightly above atmospheric pressure) to any desired maximum high pressure, and, which will operate at the minimum low pressure without back-flashing or backfiring. My invention thus provides a burner which may be used not only as a heating unit, but also as a pilot light when associated with either slow-acting thermostatic (or, other automatic) or hand-controlled means. It also insures a burner which will remain lighted when, for any reason, the pressure in the gas supply main becomes lowered almost to the pressure of the surrounding atmosphere.

Another object is to provide a burner which provides for complete combustion under all gas and atmospheric pressure conditions whereby all carbon is completely consumed, with the result that no carbon is deposited on the burner or adjacent objects even over long periods of operation; no carbon monoxide is formed; and the amount of gas required for heating is materially reduced. This insures continued maximum efficiency in operation and full benefit is at all times derived from the heat units fired.

Still another object is to provide a burner which at all times discharges a low flame, that is, a flame which projects only a slight distance above the burner at all stages of operation. It insures such a low flame under maximum pressure or gas-flow conditions that the burner may be placed very close to the object or surface to be heated without danger of the flames impinging such objects or surface, which latter condition, if permitted to exist in some instances would result in the

formation of carbon monoxide, and other well known objectionable conditions. Other advantages to be gained by the carrying out of this object are that the hot gases of combustion do not travel so far in order to contact with the surface to be heated with the result that they are influenced less by the intervening and surrounding cooler air; a smaller combustion chamber may be employed; and the burner, as well as the structure with which it is used, may be more compactly constructed.

A further object is to provide a burner which will give an intense flame and which is so constructed that the hot gases of combustion are caused to pass directly upward toward the surface to be heated within a vertical path defined, in area, substantially by the area of the burner. The burner thus has the ability to direct the hot gases of combustion positively against the intended surface without lateral dissipation—and the action is such that objects may be mounted closely to the hot-gas-travel area and closely to the sides of the burner without danger of overheating to the same.

An additional object is to provide a burner including one or more independently-acting flame discharging elements, each element embodying means for discharging a plurality of thin, and spaced edge-wise flame sheets so as to provide active flues between adjacent flame sheets which serve to automatically control the secondary air supply as the requirements in that respect vary so as to insure complete combustion at all stages of operation. This flame arrangement also contributes to the direct up-flow action of the hot gases of combustion toward the surface to which the heat is applied.

A further object is to provide a burner which is capable of exercising a positive flame-control over the volume of secondary air admitted to the combustion chamber, and which permits of limitation of such air volume to substantially that required to supply the secondary-air needs. More particularly, it is well known that a certain volume of secondary air is required to support complete combustion under each gas-flow or pressure

condition and when the amount of air admitted to the combustion chamber exceeds this requisite amount, the surplus air tends to cool the gases of combustion and render them less effective. Prior burners of this character have been so designed that an excess of secondary air must necessarily be admitted to the combustion chamber in order to have available enough air to support combustion and, for that reason, their efficiency is lowered very greatly. My invention provides a positive air-injection action which permits the use of small or restricted air openings leading into the combustion chamber. These openings may be made so small that the amount of air normally admitted is sufficient to support combustion only under the minimum low gas-flow conditions, and as the gas-flow is increased, and by the time a high pressure condition is established, the action set up by the flues between the flames, as mentioned in the preceding paragraph, causes the inflow of an additional and the requisite amount of secondary air.

Another object is to provide a burner having a plurality of gas mixing and discharging nozzles each having a plurality of flame slots therein arranged to direct thin vertical and radial flame sheets therefrom under the higher gas-flow conditions, the arrangement being such that complete combustion is effected within individual and distinct flame areas without resorting to impingement of the flames with each other. That is, the parts are so proportioned that the proper amount of secondary and primary air is induced to complete combustion in the flame area of each flame independently of the other flames.

This is a highly advantageous feature in that it causes the heat from the burner to be distributed with maximum heating effect of the B. t. u.'s fired over a greater surface in a more uniformly distributed manner. In some known forms of burners of this character, the flames are of such character that the heat is concentrated and applied to the heated surface at one place only instead of being effectively distributed over the entire flame area. In some instances the mixture streams are discharged from the burner in such a way that they are brought into confluence to complete combustion, and in such burners also, the flames tend to converge to a point from which the hotter gases of combustion are discharged so that the heat is concentrated effectively at one place only instead of over the entire surface to be heated. My invention overcomes the foregoing objectionable features by providing for distribution of the maximum heating effect over the entire flame area and over the entire surface to which the heat is applied which reduces the amount of gas required for heating.

Still another object is to provide a burner embodying one or more primary mixing no-

zles, each nozzle having mixture discharging ports which are automatically variable in active mixture discharging area as the pressure of the mixture is varied.

A further object is to provide a burner structure embodying a plurality of independently-acting mixing nozzles, each provided with means for shielding the same from flames which may be abnormally deflected from other adjacent nozzles whereby combustion is positively caused to take place only at the discharge end of such nozzles.

Additional objects are to provide a burner which discharges a flame which is confined within narrow limits, vertically and laterally, under all gas-flow conditions; to provide a burner which will function equally well with natural or artificial gas; to provide a simple and cheap burner which is adapted to give maximum efficiency under all operating conditions with a minimum of attention; to provide a burner which may be readily used with any form of water heater, furnace or boiler, etc., and which insures reduced installation, operation and upkeep costs; and to provide a burner which is well adapted for thermostatic control whether the control action be of a gradually-acting or quick acting type.

Other objects and advantages will become apparent as this description progresses and by reference to the drawings wherein,—

Figure 1 is a top plan view of one form of burner structure embodying my invention;

Fig. 2 is a side elevation, partially in section, of the burner structure shown in Fig. 1;

Fig. 3 is an enlarged elevational view of one of the discharge nozzles and a portion of the burner head;

Figure 4 is an enlarged, central, vertical sectional view through one of the discharge nozzles;

Fig. 5 is a front elevation of one of the nozzle mixture tubes with the cap removed.

Fig. 11 is a view similar to Fig. 10 except illustrating the character of the flame at a slightly-increased-pressure stage;

Fig. 12 is a view similar to Figs. 10 and 11, except illustrating the character of the flame at a still further increased pressure stage;

Fig. 13 is another view similar to 10, 11 and 12, but illustrating the character of the flame under high gas pressure conditions; and

Fig. 14 is an elevational view, partially in section, of a thermostatically-controlled water heater having my invention applied thereto.

With particular reference to the form of burner structure shown in the drawings, I provide a burner head 15 having a plurality of horizontally projecting arms 16, each of which is adapted to removably support a burner nozzle structure 17. The interior of the burner head 15 and the connected arms 16 is hollow to provide a gas distributing chamber 18 (Fig. 4) which is in communication with each of the nozzles, such chamber being, in turn, in communication with a gas source (not shown) through a suitable conduit 19 (Fig. 1). The particular form of burner which I have chosen to illustrate my invention is well adapted for use with a water heater and the particular horseshoe-shaped burner head is arranged to embrace a centrally disposed heater drain pipe as will be explained more specifically hereinafter. Also, while I have shown the burner head as having six projecting arms 16, and a like number of nozzles 17, it is to be understood that the number of arms and nozzles may be varied to suit the particular conditions of use.

The nozzle structures 17 each function independently as separate units to discharge a plurality of independently effective flames under perfect combustion conditions. Specifically, each nozzle embodies a mixing tube 20 (Figs. 3 and 7) having a lower threaded end 21 adapted to engage a threaded opening 16^a in the supporting arm 16; and it is further provided with a thickened body wall 22 above such threaded portion, such wall having an external polygonal shape to permit the same to be readily grasped by a wrench for tightening the nozzle in place upon the burner arm. This tube has an axial bore 23 which extends from its upper end to, preferably, a point near its bottom, and adjacent the lower part of said thickened body wall 22. A frusto-conical opening 24 is provided in the lower end 21 of the tube with its lower enlarged end in communication with the gas distributing chamber 18, and its upper and reduced end in communication with a short and small-sized axial passage 25. This passage 25 is adapted to discharge a fine axial stream of gas from the distributing chamber 18 into and axially through the tube bore 23.

In carrying out my invention, I provide for the formation of a combustible mixture within the tube bore 23 and, to this end, I provide a plurality of primary air openings 26 at the lower end of the tube which lead, preferably, through the thickened tube walls into the lower part of the tube bore to admit atmospheric air thereto. These air openings 26 extend inwardly and upwardly with their inner ends above the outlet surface of the gas

discharge port 25, so that primary air is drawn in by the injector action set up within the tube by the axially flowing gas stream, as will be well understood. The openings 26 are of such size that their total area is considerably greater than the area of the tube bore 23 whereby the flow of air into the tube is accomplished without restriction, and sufficient air is entrained and admixed with the gas in the tube bore to form therein a combustible mixture.

In the use of a burner under conditions where the gas pressure may fluctuate over a wide pressure range from a pressure only slightly above atmospheric pressure, it is essential that back-flashing and back-firing during low pressure operation be prevented. The relative proportions of the gas discharge orifice 25, the air inlet openings 26 and the tube bore 23, are such that back-flashing or back-firing will take place unless further mixture control means is employed. More specifically, the relative proportions of these particular mixture-forming elements, which I employ, are such that when the gas-flow approaches or is reduced to a low pressure point, the rate of mixture flow becomes lower than the rate of flame propagation for the particular mixture fired with the result that the mixture fires back toward the gas source and burns at the base of the mixing tube bore. Such an arrangement if not compensated for, would render use of a burner of this character prohibitive, for reasons which will be appreciated by those skilled in the art.

To complete my burner nozzle and to insure a smooth and even flame with proper combustion under all gas pressure conditions without back-flashing and/or back-firing, I employ mixture discharge-control means which includes a cap 27 adapted to be mounted upon the upper end of the nozzle tube 20. This cap is provided with an internally-threaded skirt portion adapted to engage the threaded portion 28 formed near the upper end of the tube, this threaded portion being of lesser diameter than the body 20^b of the tube so as to provide a shoulder upon which the bottom of the cap seats to establish a predetermined relation between the cap and the discharge end of the tube as will be explained more fully hereinafter. The upper end 20^b of the tube is still further reduced in outside-diameter to provide a very shallow space 29 between the adjacent side wall surfaces of the tube end 20^b and the inner wall surface of the cap.

The mixture-discharge-control cap is provided with a plurality of, preferably four, longitudinal, and radially-cut, flame slots 31 which terminate short of the top and bottom thereof so as to provide a horizontally-deflecting wall surface 30 in the extreme central top curved portion of the cap. The reduced tube end 20^b is of such length that when the cap is screwed down against the shoulder at

the top of the tube body portion 20^a, a relatively small space 32 is provided between the upper end of the tube 20 and the upper inner wall surface of the cap. The upper end of the tube is so spaced from the cap that the narrow annular side space 29 is in communication with, and forms a downward continuation of, the space 32.

While the structural relationship between the several parts so far described contributes to the results attained in the use of my invention, the relative areas of the slots 31, the mixing tube outlet and the spaces 29 and 32 at the outer end of and adjacent the outer end 15 side wall of the mixing tube, respectively, also contribute to the accomplishment of such results. Specifically, the slots 31 are each, preferably, of such dimensions in width and length that the sum of the areas of the slot 20 portions outwardly beyond the discharge end of the mixing tube 20 is less than the area of the mixing tube outlet. Further, the space 29 extending adjacent the side wall of the tube 20 at its discharge end surrounds such 25 end of the tube and is shallow as compared to the space 32 in axial alignment with the discharge end of the tube so that the "orifice area," as I may term it, at the juncture of the connected end and side spaces is restricted, 30 preventing a free flow or expansion of the mixture from the end space 32 into the side space 29. I further, preferably, provide the slots 31 with such dimensions in width and length that the sum of the areas of the slot 35 portions outwardly beyond the discharge end of the mixing tube 20, and outwardly beyond the juncture between the end and side spaces 29 and 32, is greater than the "orifice area" at the juncture of such connected end and 40 side spaces, and also greater than the cross sectional area of the side space 29. These relative areas have to do with the automatic variation of the active mixture-discharging area of the slots 31, which will be referred 45 to further hereinafter.

In the operation of the structure so far described, when the gas flow is at a minimum low point (which may be only slightly above atmospheric pressure) the thin gas stream 50 discharging at a relatively high velocity through the orifice 25 into the tube bore 23 entrains primary air through the openings 26, the amount of air admitted being such that the admixing of the same with the gas 55 as it passes through the tube provides a combustible mixture. This mixture is discharged from the tube bore in an axial stream into the space 32. At this low pressure stage, it appears that the total active slot area (or 60 the area of the upper surfaces of the slots 31 in direct-flow communication with the chamber 32) is such that the mixture fed into the chamber will be discharged directly through the upper slot surfaces. In other words, the 65 active slot area is such that, under that low

gas-flow or pressure condition, the mixture is discharged through the slots as fast as it is delivered to the chamber 32. Under these conditions, as the mixture passes through the slots 31 and is fired, a very low pilot-like flame burns at the surface of the slots approximately within the vertical limits of the nozzle as indicated in Fig. 10. The flames which burn from the surfaces of these slots, due to the foregoing described arrangement of parts, are so-called "soft" flames which will continue to burn at the surface of the respective flame slots when subjected to even severe draft and other critical tests. These flames are also of minimum intensity, and the gas flow or pressure may be lowered to such a point that these pilot flames do not have appreciably any heating effect. Also, regardless of the low pressure condition existing at this time, back-firing does not take place; because the restriction condition established by each separate slot in the discharge of its proportionate part of the mixture is such as to set up (even at the lowest gas pressure) a mixture velocity flow through each 80 slot which is greater than the rate of flame propagation for the mixture being fired.

When the gas flow is increased from the minimum low-pressure point, the mixture flow through the tube bore 23 is likewise increased. As this increase takes place, a greater pressure condition is set up within the chamber 32 due to the fact that the total-area of the upper part of the flame slots 30 in direct communication with the chamber 32 is not such that the mixture will be discharged therethrough as fast as it is fed into the chamber 32. Thus, as the pressure is increased, the skin-flame of Fig. 10, at an intermediate pressure stage, is transferred into a plurality of independent flame jets such as indicated in Fig. 11. As the pressure continues to be increased from the stage shown in Fig. 11, and the pressure in the chamber 32 is likewise increased, the resulting back-pressure condition causes the mixture to back-up into the annular space 29 at the side of the mixing tube end 20^b and downward through the slots 30 whereby the mixture will be discharged and will burn to a lower, or further rearward, point 100 along the flame slots 31. At this stage, the jets may take a form somewhat similar to that shown in Fig. 12, the progressive action being compared in a way to the unfolding of the petals of a flower bud. These jets take the form of independently-acting sheets of flame, the depth of the flame depending upon the pressure of the mixture and the extent to which the mixture is forced down toward the bottom of the slots. Finally, at the maximum 110 high gas flow or pressure point, the back pressure effect is such as to cause the mixture to discharge horizontally throughout the length of the slots to produce a plurality of thin and radially directed flame sheets substantially of 120 125 130

the shape shown in Fig. 13. This arrangement is such that, at all stages, the flames are smooth and stable and there is no flickering along the slot surfaces. The active slot discharging area varies with the gas pressure and the mixture will burn only in areas defined by the slot-discharging areas then active.

Even under highest gas pressure conditions, the flames are of such a character, due to the arrangement of the mixture-control elements, that they extend only a slight distance vertically and laterally beyond the burner surface, as will be obvious from Figs. 10-13, inclusive. Thus, the individual flames are capable of burning with complete combustion within their respective flame areas without impinging each other so that full heating benefit is derived from each individual flame. This is an important phase of my invention, in that it enables the burner to be located close to the surface to be heated without the danger of formation of carbon monoxide in any instance; more compact structures may be employed; and greater heating efficiency is provided for with less cost.

My invention further provides for complete combustion under all gas-flow conditions thereby insuring complete consumption of all of the carbon content of the flame, so that there will be no soot or carbon deposits upon the burner to clog the same or upon the surrounding objects which are subjected to the action of the burner. More particularly, the nozzles are carried by the arms 16 which project outwardly from the burner head to such an extent as to permit a free upward flow of secondary air around all sides thereof. The flames issuing from the flame slots 30 are thus subjected to a free up-flow of secondary air which is a requisite of complete combustion. Under high gas pressure conditions, with the thin vertical sheets of flame projecting from the radial flame slots 31, the flame sheets establish flues between adjacent flames which set up an increased secondary air induction or injector condition between the thin flame sheets which is sufficient to supply the secondary air necessary for complete combustion. This injector action varies with the gas pressure and flame condition, but it is always sufficient to insure the proper amount of secondary air. Complete combustion in each independent flame area is further aided by the segregation and firing of the mixture in the vertical thin sheet formation as will be well understood. It will be obvious that the usual secondary air opening leading into the combustion chamber may be reduced to a minimum size, and, in fact, this opening may be of no greater area than necessary to normally supply sufficient air to support combustion at the minimum low-flame stage such as illustrated in Fig. 10. In such case, the injector action of the burner will induce the additionally required air through such opening to support combustion,

at increased gas-flow stages. This is important as it prevents cooling of the gases of combustion by excess secondary-air as hereinabove explained.

Another outstanding feature of my invention is that the hot gases of combustion are caused to flow directly upward from the burner in a vertical path bounded substantially by the surface of the burner. This condition is provided for, in part, by setting the nozzles outward from the burner head so as to permit a free flow of air up and around the same and, in part, by the character of the flame sheets which define the V-shaped flue channels. These flue-channels appear to create a vertical up-draft strong enough to draw in and confine the heated gases as above stated. This effect is very pronounced and the upward movement of these gases is so direct, without lateral spreading or dissipation, that an object can be readily inserted within the circle defined by the nozzles (as at A in Fig. 1) or an object may be passed around and close to the outside of the ring of nozzles (as indicated generally at B in Fig. 1) without overheating of the same. This is a very important factor in present-day use of burner constructions where it is highly desirable to conserve space in that it enables the burner to be mounted in a small combustion chamber with a minimum of heat insulation and the burner may also be located close to a floor or wall surface without danger of overheating of such surface. Previous burners offer serious objection in this respect, requiring in many instances (water heater installations, for example) the use of excessively large combustion chambers and the use of expensive insulating means.

The air openings 26 of each nozzle are shielded from flames which may be abnormally deflected downward from adjacent nozzles so as to positively guard against firing of the mixture at any point other than at nozzle caps 30. To this end, I provide an inverted cup-shaped member 33 (Fig. 9) which is adapted to be passed down over the nozzle and seated upon the top part of the enlarged body portion 22 so that its depending skirt 33^a passes down over and beneath the inlets to the air passages 26 (Fig. 4) to shield the same. This shield member is of such size that it does not restrict the flow of air to and through the primary air openings 26. The upper wall of this shield is provided with a plurality of openings 34 and its use does not interfere with the foregoing described secondary air draft actions set up by the flames. These openings 34, in fact, may set up an air induction action at the top of the shield and flames which may be directed toward the openings 26, may be deflected by this draft condition toward the upper part of the shield and away from the open bottom of the shield and the primary air inlets.

From the foregoing, it will be appreciated that my invention is well adapted for use with water heaters wherein the gas-flow is controlled between high and low pressure points by thermostatic means, and its application in such case will be better understood by reference to Fig. 14 of the drawings showing a certain form of heater structure. The heater which I have shown comprises a storage tank 35 having a combustion chamber 36 therebeneath. A water spreader 37 of well known form is mounted in this chamber with a burner embodying my invention mounted beneath so that the hot gases from the burner 15 will strike the spreader bottom wall 37a. The gas flow is controlled by a slow-acting thermostatic device 38 which, as will be well understood from the term "slow acting", functions, under the control of the temperature of the water, to vary the gas flow progressively from a minimum low pressure point to a maximum, and vice versa. More particularly, when the water is cold the thermostatic means will function to supply gas at a maximum pressure and, as the water becomes heated, the gas flow is cut down accordingly; and the gas pressure condition fluctuates back and forth as water is drawn from the storage tank to maintain the temperature of 20 the water at the desired temperature. There will be periods of quite long duration when no water will be drawn from the tank, at which time the thermostat will function to cut the gas flow down to a minimum point. 25 This minimum point must be such that the B. t. u.'s fired will not be sufficient to cause overheating of the water in the tank. One of the serious difficulties experienced with prior burners is that this desired low gas-flow or pressure point cannot be established without back-firing of the burner,—with the result that the low gas pressure point must be at such a high point (to prevent back-firing) that the B. t. u.'s fired cause overheating of the water. 30 My burner, which, as above described, is of such construction as to eliminate back-firing at even the lowest gas pressure (which is slightly above atmospheric pressure) and overcomes the foregoing objectionable features in heater operation. The danger of overheating the water under any condition is positively eliminated. Also, the advantages in this respect will be readily understood when my burner is used 35 in conjunction with furnaces and boilers for heating systems, stoves, gas refrigerators, vats, etc.

It will be noted in Fig. 14 that the burner is located very close to the bottom 37a of the spreader. This can be done with my invention without the flames impinging the spreader due to the ability of the burner to discharge, even at the maximum pressure point, a very low flame. This is quite an 40 important matter in water heater operation;

because, if the flames should impinge the spreader bottom which supports a cooler body of water, carbon monoxide would be formed. The character of the flames discharged also permits the heater drain pipe 39 to be passed down within the circle of burner nozzles 17 without the flames impinging thereon and causing the above-mentioned prohibitive results. The foregoing advantages cannot be obtained with prior known forms of burners of this character, all of which are so designed that they discharge a high flame under high and intermediate pressure conditions, and their flames tend to spread to such an extent that they would impinge the heater drain 45 pipe if used similarly to my burner. 50

The ability of my burner to burn at all pressure stages with complete combustion, and its ability to confine the heated gases to a vertical path substantially defined by the area of the burner, further renders it very valuable for use with water heaters. As will be obvious from Fig. 14, the hot burner gases will all be directed toward and uniformly distributed against the bottom 37a of the spreader whereby they heat such surface to a maximum degree and insure maximum efficiency 55 of the spreader. 60

In addition to the foregoing features, my invention makes possible the use of a very small heater combustion chamber 36; the heater as a whole can be made smaller with the same or greater water-handling capacity; the heater can be mounted closer to the floor or wall surface (with the burner very close 65 to such surface) without danger of overheating or setting fire to such surface; expensive insulation of the combustion chamber walls is not required; and the efficiency and cost of construction, upkeep and operation of the 70 heater as a whole are materially reduced. The heater can be operated over any desired 75 gas-pressure range in any locality, regardless of varying gas and atmospheric pressure conditions without depreciation in any of the advantages hereinbefore mentioned. 80

It will be understood that while I have shown and described only one form of my invention, various changes may be made in details and arrangement of parts without departing from the spirit and scope of my invention as defined by the claims which follow. For example, the nozzles may be spaced farther apart and they may be varied in size; the caps may take different shapes; and in some instances the flame slots in adjacent nozzles may be so arranged that the flame sheets issue from one nozzle in staggered relation to the flames issuing from the adjacent nozzles 85 as indicated generally in Fig. 1,—however, in the form described, the nozzles are so spaced and the character of the flames is such that the caps may be screwed home irrespective of the relative positions of the flame slots 90

of adjacent nozzles without impingement of adjacent flames.

I claim:

1. A gas burner which comprises means for forming a combustible mixture including a chamber in which the mixture is formed and from which it is discharged, and means for discharging the formed mixture into a combustion zone which includes a plurality of mixture outlets communicating with the discharge point of said chamber and each of which has a discharging area disposed behind the point of discharge from said chamber.
- 10 2. A gas burner which comprises means for forming a combustible mixture which includes a chamber having an open end from which the formed mixture is discharged, and means for delivering the mixture discharged from said chamber into a combustion zone, which means includes a plurality of slots communicating with the discharge end of said chamber and which are of a length to extend beyond the discharge end of said chamber in a direction opposite the direction in which the mixture is discharged.
- 15 3. A gas burner comprising means for forming a combustible mixture including a chamber having a discharge opening and means for delivering the formed mixture from said chamber to a combustion zone which includes a plurality of slots which are of such length as to extend both in front of and to the rear of said discharge opening.
- 20 4. A gas burner comprising means for forming a combustible mixture including a chamber having a discharge opening and means for delivering the formed mixture from said chamber to a combustion zone which includes a plurality of slots which are offset laterally from said discharge opening and which are of sufficient length to extend behind such opening.
- 25 5. In a gas burner, means including a mixing tube for forming a gas and air mixture, a cap telescoping the discharge end of said tube and spaced therefrom providing a space into which the mixture is fed from said tube, and slots formed lengthwise in said cap and of sufficient length to extend behind the outlet of said mixing tube.
- 30 6. In a gas burner, means including a mixing tube for forming a gas and air mixture, a cap telescoping the discharge end of said tube and spaced therefrom providing a space into which the mixture is fed from said tube, said cap having an end surface in substantially axial alignment with the discharge end of said tube and a body surface extending substantially parallel with the side wall of said tube, and slots formed lengthwise in said cap and extending from said end surface along said body surface substantially parallel with the axis of said tube to a point rearward of
- 35 said tube discharge end.

7. A gas burner comprising means, including a chamber having an outlet, for forming a gas and air mixture, and means for discharging said mixture into a combustion zone which includes a plurality of slots which have one portion of their slot surfaces in direct flow alignment with the outlet from said chamber and another portion of their slot surfaces in indirect flow alignment with said chamber outlet.

8. A gas burner which comprises means for forming a gas and air mixture which includes a mixing chamber, and an imperforate element at the outlet end of and axial with respect to said chamber which the mixture engages in discharging, said baffle element having its surface which is exposed to the discharging mixture of less cross sectional area than the cross sectional area of the discharge end of the mixture chamber, and means providing mixture discharge outlets adjacent the discharge end of said chamber cooperating with said baffle element to discharge the mixture from said chamber.

9. In a burner, a gas and air mixture forming chamber having a discharge opening, a member associated with the discharge end of said chamber having a horizontally disposed baffle surface spaced outwardly from and substantially axial with respect to said discharge opening, the horizontal projection of said baffle surface being of less dimension than said discharge opening, and said member having discharge outlets cooperating with said baffle surface for the delivery of the mixture for combustion.

10. In a burner, a gas and air mixture tube, a cap over the end of said tube and having a horizontally disposed imperforate baffle surface in its end spaced from and in axial alignment with the discharge end of said tube, the horizontal projection of said baffle surface being of less dimension than the width of the discharge end of said tube, and slots in said cap extending from said baffle surface down along the sides of said cap cooperating with said baffle surface for the delivery of the mixture for combustion.

11. In a burner, a gas and air mixture tube, a cap telescoping the discharge end of said tube, said cap having a rounded inner end part, the inner end part of said cap being in spaced and axial alignment with the discharge end of said tube, the horizontal projection of said end part being less than the width of the discharge end of said tube, and spaced apart slots in said cap extending from said cap end part along the sides of said cap in a direction substantially parallel to the axis of said tube.

12. In a burner, gas and air mixture means which includes a mixing tube, a cap having one end closed and mounted over the discharge end of said tube, the closed end of said cap being in the form of a horizontally-

- disposed and concaved surface exposed to the axial discharge of the mixture from said tube, the width of said end surface being less than the width of the discharge end of said tube, and slots in said cap extending away from said end surface. 70
13. In a gas burner, means for forming a gas and air mixture which includes a mixing chamber having a discharge outlet, means for feeding the mixture delivered through said outlet for combustion purposes which includes a plurality of slots which have an active discharging area forwardly of the discharge end of said chamber, the sum of the areas of the slot portions forwardly of the discharge end of said chamber being less than the area of the mixing chamber discharge outlet. 75
14. In a burner, means providing a gas and air mixing chamber having an outlet, delivery means mounted over said outlet which includes a plurality of slots which extend forwardly of and behind the chamber outlet, the sum of the areas of the slot portions forwardly of said outlet being less than the area of said outlet. 80
15. In a burner, a gas and air mixing tube having an outlet, a cap mounted over said outlet in spaced relation thereto, said cap having a plurality of substantially length-wise-directed slots therein which are of sufficient length to extend both forwardly of and behind said tube outlet, the sum of the slot areas forwardly of said tube outlet being less than the area of the tube outlet. 85
16. In a gas burner, a mixing tube having provision for the forming of a gas and air mixture therein and having an outlet at one end, a member mounted over the outlet end of said tube in spaced relation thereto providing a space at the end and along the side of said tube, and elongated discharge outlets in said member communicating directly with said space both at the end and along the side of said tube, the sum of the areas of the outlets communicating directly with the end part of said space being less than the area of the outlet end of said tube. 90
17. In a gas burner, a gas and air mixing tube having an outlet, a cap telescoping the outlet end of said tube providing a space at the end of said tube and along its side wall, said cap having slots each of sufficient length to communicate with both said end and side spaces, the sum of the areas of the slot portions communicating directly with said end space being less than the area of said tube outlet. 95
18. In a gas burner, a tube with an outlet and having provision for the forming of a gas and air mixture therein, means associated with the outlet end of said tube providing a space at the end of said tube and a comparatively narrow space around the side of the tube adjacent its outlet end, said means including slots of a length to extend into communication with both said end and side spaces, the sum of the areas of the slot surfaces communicating with said end space be- 100
- cluding slots of a length to extend into communication with both said end and side spaces, the sum of the areas of the slot portions communicating with said end space being less than the area of the tube outlet. 105
19. In a gas burner, a mixing tube having provision for the forming of a gas and air mixture therein and having an outlet at one end, a member mounted over the outlet end of said tube in spaced relation thereto providing a space at the end and along the side of the tube, and discharge outlets in said member communicating with said space both at the end and along the side of said tube, the sum of the discharge outlet areas communicating directly with the end part of said space being greater than the cross sectional area of the part of said space at the side of said tube. 110
20. In a gas burner, means providing a chamber having an outlet and having provision for the forming therein of a gas and air mixture, a member mounted over said chamber outlet providing a space forwardly of and extending behind said chamber outlet, said member having outlets communicating with said space both forwardly of and behind said chamber outlet, the sum of the areas of the outlet portions forwardly of said chamber outlet being greater than the cross sectional area of said space at the juncture of its portions which are disposed forwardly of and behind said chamber outlet. 115
21. In a gas burner, a gas and air mixing tube having an outlet, a cap telescoping the outlet end of said tube providing a space at the end of said tube and with an extension along the side wall of said tube, said cap having slots of sufficient length to communicate with both said end and side space sections, the sum of the areas of the slot surfaces communicating directly with said end space section being greater than the area of the space at the juncture of said end and side space sections. 120
22. In a gas burner, a gas and air mixing tube having an outlet, a cap telescoping the outlet end of said tube providing a space at the end of said tube and along its side wall, said cap having slots of sufficient length to communicate with both said end and side spaces, the sum of the areas of the slot portions communicating directly with said end space being greater than the cross-sectional area of the side space. 125
23. In a gas burner, a tube with an outlet and having provision for the forming of a gas and air mixture therein, means associated with the outlet end of said tube providing a space at the end of said tube and a comparatively narrow space around the side of the tube adjacent its outlet end, said means including slots of a length to extend into communication with both said end and side spaces, the sum of the areas of the slot surfaces communicating with said end space be- 130

ing greater than the cross-sectional area of the side space.

24. In a gas burner, a tube with an outlet and having provision for the forming of a gas and air mixture therein, means associated with the outlet end of said tube providing a space having a section at the end of said tube and a comparatively narrow section around the side of the tube adjacent its outlet end, and connected to said end section, said means including slots of a length to extend into direct communication with both said end and side space sections, the sum of the areas of the slot portions communicating directly with said end space section being greater than the area of the connection between said end and side space sections.

25. In combination, a combustion chamber, and a burner structure mounted in said chamber which includes a gas and air mixing chamber having an outlet, a trap communicating with said mixing chamber outlet and having associated therewith a baffle and discharge slots so related as to discharge the mixture through said slots in spaced sheet formation, the depth of the flame sheets being caused to vary with mixture pressure variation to provide variable depth flame flues, said combustion chamber having air inlet means of such size and capacity as to admit under normal draft conditions to the combustion chamber only a sufficient amount of air to supply combustion needs under minimum gas pressure operation, said flame flues self-inducing through said air inlet means a proportionately increased amount of air as their depth is increased by a gas pressure increase.

26. In combination, a shallow combustion chamber, and a burner mounted in said combustion chamber, said burner comprising nozzle structure which takes the form of a vertically-disposed tube having provision for the forming of a combustible mixture therein, mixture-discharge-control means associated with said tube including slotted mixture discharge openings for causing the mixture to burn in spaced flame sheets from the surfaces of said openings and for directing said sheets horizontally away from said nozzle, said combustion chamber having its sole air inlet restricted to limit the amount of air admitted therethrough under normal draft conditions to that required only for minimum combustion needs, said flame sheets defining flame flues which self-induce through said air inlet additional air proportionately as the size of said sheets and flues is varied by mixture pressure variation.

27. A gas burner including a mixture forming and discharge-controlling nozzle which comprises a tubular body portion having provision for the forming of a combustible mixture therein, a cap mounted on the outer end of said body in spaced relation thereto providing a chamber beyond the outer end of

said body and a relatively shallow chamber substantially uniform in cross section around the side of said body adjacent its outer end, said cap having a plurality of equally spaced slots extending lengthwise from near its top central part down along the cap sides, communicating at different points directly with said chambers at the end and side of said body, the top central part of said cap being imperforate and serving as a baffle directing the mixture laterally as it is discharged from said body toward said slots.

28. In a gas burner, an element for forming a combustible mixture and means for discharging said mixture for combustion including a plurality of laterally-directing ports relatively located to discharge into independent zones, a portion only of each of said ports being directly in the flow path of said mixture, and the remaining portion of each said port being so located as to bear an indirect and rearward relation to said direct-flow path.

29. A mixture forming and discharging device for a gas burner which has a mixing tube with an axial discharge opening and provision for forming a combustible mixture therein, a member mounted upon the outer end of said tube and having a part which extends rearwardly of said discharge opening and substantially parallel with the end wall of said tube in spaced relation thereto for forming a mixture pressure space between said tube and member, and comparatively long discharge outlets leading from the space between said tube and the rearwardly extending member part, said outlets being so restricted that the flow rate of the mixture therethrough is greater than the rate of flame propagation for mixture fed under the minimum pressure.

30. In a gas burner, the combination with a hollow gas distributing head, of means in communication with the interior of said head for forming and delivering a combustible mixture for combustion purposes including a mixing tube having an outlet, means for forming a combustible mixture within said tube, cap means for forming a small chamber at the end of said tube for receiving the already-formed mixture from said outlet, and elongated slot means for delivering individual streams of said mixture directly into individual, separated flame areas, the active area of said slot means being of such size relative to the tube outlet as to establish a mixture discharge flow velocity therethrough which is at all times greater than the rate of flame propagation for the mixture fired.

31. In a gas burner, a jet device comprising a tube having a mixing bore, means for admitting gas and air to said tube to form a combustible mixture therein, an end part for the discharge end of said tube having a larger bore than said mixing bore, long, nar-

row slots in the wall of said end part extending rearwardly of the discharge end of said mixing bore for discharging the mixture from the bore into a combustion zone, and another end part located axially with respect to the bore of said first end part and tending to deflect the mixture laterally through said slots.

32. In a gas burner, a mixing device having an upper open-ended tubular portion, means for forming a combustible mixture within the tubular portion; and mixture-discharge-control means comprising a cap having a comparatively long body adapted to be mounted at and over the end of said tubular portion in spaced relation thereto with its body extending adjacent the sides of said tubular portion to provide a mixture-receiving chamber at the end of said tube which is of inverted U-shape in longitudinal section, and said cap having narrow, independently-acting slits extending longitudinally thereof and of such length as to extend adjacent the side of said tubular portion, said slits being so arranged relative to each other that the mixture is discharged from said chamber into a plurality of separated flame areas.

33. In a gas burner, a mixing device having a vertical, open-ended tubular portion with provision for the forming of a combustible mixture; and mixture-discharge-control means comprising a cap mounted over the end of said tubular portion in spaced relation thereto with its body extending adjacent the side of the tubular portion to provide a mixture-receiving chamber at the end and side of said tube, and narrow, radial slits in and extending lengthwise of said cap and of such length as to extend parallel and adjacent to the side of said tubular portion, the arrangement being such that only a portion of each said slit is in a direct line with the open end of said tubular portion and in direct communication with said chamber, said slits being so arranged relative to each other that the mixture is discharged therethrough from said chamber into a plurality of different flame areas, and the minimum active area of each of said slits is of such size that, under minimum gas pressure operation, the portion of the mixture which passes through each of the same is caused to flow at a rate greater than the rate of flame propagation for that particular mixture.

34. In a gas burner, means including a vertical mixing tube for forming a combustible mixture, and means mounted upon said tube for controlling the discharge of said pre-formed mixture, said latter means comprising a cap so shaped and adapted to fit over the discharge end of said tube in spaced relation thereto that a mixture-receiving chamber of substantially inverted U-shape in cross section is provided, said cap having narrow, ra-

dial slots extending lengthwise thereof and terminating at its closed end portion, said slots being of such length that they extend in part parallel and adjacent to the side of the tube wall and in part above the end of the tube so that a part thereof is in direct line flow with the discharge end of said tube, and said slots being of such size that the total area of that portion thereof in direct communication with the end of said tube is such that under certain gas pressure conditions the mixture discharged from the tube is delivered from said chamber through the direct flow slot portions as fast as it is fed into said portion whereby the mixture will burn, when ignited, at the surface only of said then active and direct flow slot portions.

35. In a gas burner, means for forming a combustible mixture including a mixing tube, and a mixture-discharge-control means associated with said tube comprising a cap supported over and surrounding the discharge end of said tube in spaced relation thereto providing a mixture-receiving chamber having a portion in axial alignment with said tube and a more restricted portion alongside said tube, said cap having narrow slits therein serving as the sole means for discharging the mixture from said chamber, said slits terminating short of the top of said cap to provide in the top central portion of the latter a horizontally-deflecting wall surface in axial alignment with and of lesser dimension than the bore of said tube, said slits being long enough to extend down adjacent the side of said tube to receive and discharge the mixture from said chamber at that point as the mixture is backed up therein by increase in mixture pressure.

36. In a gas burner, means for forming a mixture of gas and air including a vertical tube, a cap having a top and side wall mounted over the discharge end of said tube, said tube end being projected within said cap close to the top thereof and the outside dimensions of said tube being reduced to provide a substantially parallel shallow space between it and the cap side wall as well as an end space between it and the cap top wall, narrow, radial slits extending lengthwise of said cap from a point near the top of said cap from above said tube end to a point near the bottom of its side alongside the reduced portion of said tube end.

37. In a burner, a vertically disposed nozzle provided with a discharge outlet and having provision for forming therein a combustible mixture, a vertically slotted member telescoping the discharge end of said nozzle in spaced relation to the end and side of said nozzle, said member having a baffle wall surface in axial alignment with said nozzle and of less width than the discharge outlet of said nozzle tending to deflect mixture streams through the slots of said member laterally, said slots

being substantially spaced from each other and sufficiently separated for confining the burning mixture to individual flame zones and for effecting substantially complete combustion at the high gas pressure without impairment of the flames one with the other.

38. In a burner, a vertically disposed nozzle structure, including means for forming a combustible mixture therein, a vertically slotted member telescoping the discharge end of said nozzle in spaced relation thereto at its end and sides, said member having a baffle wall surface in axial alignment with the nozzle bore for deflecting mixture streams through the slots of said member laterally within a vertical limit defined substantially by the height of said baffle wall, said slots being disconnected and sufficiently spaced from each other as to confine the ignited mixture burning therefrom to individual flame zones and also providing spaced flame sheets which define distinct unobstructed vertical flame flues for inducing a positive flow of secondary air upwardly around said nozzle and between the flame sheets.

39. The combination in a burner, of a plurality of flame discharge elements, each element comprising a vertical tube having a mixing bore, air openings in said elements at the base of said bore through which primary air is entrained for forming the mixture, means for discharging lateral, edge-wise flame sheets supported by said mixture, and means carried by each said element and passing down over said air openings at such a distance therefrom as to not restrict the flow of air therethrough to shield such openings from flames which may be abnormally deflected theretoward from adjacent flame elements.

40. In a gas burner, a tube having provision for forming a combustible mixture therein, and means for discharging the mixture directly from said tube which comprises a cap member mounted upon said tube with its closed end disposed in spaced axial alignment with the end of the tube to present a non-perforated concaved surface to the end of the tube, and the side wall of said cap member passing down adjacent the tube wall in shallow spaced relation thereto, said cap member having long slots extending from its non-perforated end part along the part adjacent the side wall of said tube, with a part only of each slot disposed in flow alignment with the end of said tube, the total area of all the slots in flow alignment with said tube being great enough to discharge the mixture as fast as fed from the tube under a lower gas pressure condition, the mixture being backed-up in the slots as the pressure is increased beyond the capacity of the direct flow area.

41. In a gas burner, a tube having provision for the forming of a combustible mix-

ture therein, and means for discharging the mixture directly from said tube which comprises a bullet-shaped cap member mounted over the end of said tube with its nose part in substantially axial alignment with the bore of said tube, said cap member having its nose and body parts spaced from the end and side well of said tube to provide a mixture-receiving space, said cap member having a plurality of separated slots extending from adjacent its nose part along its body so that a part of each slot is in substantially direct flow alignment with said tube and a part communicates with the space alongside said tube.

42. In a gas burner, a tube having provision for the forming of a combustible mixture therein, and means for discharging the mixture directly from said tube which comprises a bullet-shaped cap member mounted over the end of said tube with its nose part in substantially axial alignment with the bore of said tube, said cap member having its nose and body parts spaced from the end and side walls of said tube to provide a mixture-receiving space, said cap member having a plurality of separated slots extending from adjacent its nose part along its body so that a part of each slot is in substantially direct flow alignment with said tube and a part communicates with the space alongside said tube, said slots being of such width that under certain gas pressure conditions the total area of those portions in direct flow alignment is sufficient to discharge the mixture therefrom without back-up in the other portions of said slots.

43. In a gas burner, a vertically disposed tubular member having provision for forming a combustible mixture, and delivery means which includes a hollow tip having an imperforate end part spaced from and in axial alignment with said tubular member but not entirely covering the end of the latter in horizontal projection and a side wall part extending adjacent the side of said tubular member in spaced relation, and delivery slots in said tip extending from said end part in flow alignment with said tubular member into said side wall part, said end part serving to deflect the mixture from said tubular member through the adjacent slot portions.

44. In a gas burner, means including a tube for forming a combustible mixture, and a cap member mounted over the discharge end of said tube in spaced relation thereto with an end wall part axially aligned with said tube and another part extending adjacent the side of said tube providing end and side spaces associated with the discharge end of said tube, said cap having disconnected slots of such narrowness as to materially restrict the flow of the mixture through each of them, said slots being of such length that a part of each of them is located in the end part of

the tube in substantial axial flow alignment with said tube and the other part extends adjacent the side of the tube out of axial flow alignment, the total area of the portions of the slots in axial flow alignment being greater than the orifice area of the space connecting said end and side spaces.

5 In testimony whereof, I have subscribed my name.
